UNITED STATES PATENT OFFICE.

CARL M. HUGULEY, OF SAN DIEGO, CALIFORNIA.

MOP HEAD.

Application filed August 15, 1927. Serial No. 212,932.

My invention relates to mops, more particularly to mop heads, and the objects of my invention are: first, to provide a mop head which, when fastened on the mop handle, will secure the mop in position and prevents its slipping or moving; second, to provide a mop head which may be readily secured or removed from a mop handle; third, to provide a mop head of this class in which 10 a bolt holds the mop head clamped on the mop so that the mop head and mop may be readily shipped or transported intact without the handle portion; fourth, to provide a mop head of this class which is rigidly secured to the mop handle by a single, easily removable bolt; fifth, to provide a mop of this class in which the mop, the head and the handle may be readily assembled or the mop head and mop may be readily positioned 20 on the handle and secured thereto so that it will not loosen; sixth, to provide a mop head of this class which is very simple and economical of construction, durable, easy to assemble, and which will not readily deteriorate or get out of order.

With these and other objects in view, as will appear hereinafter, my invention consists of certain novel features of construction, combination and arrangement of parts 20 and portions as will be hereinafter described in detail and particularly set forth in the appended claims, reference being had to the accompanying drawings and to the characters of reference thereon, which form a part 30 of this application, in which:

Figure 1 is a side elevational view of my mop head in connection with the mop strands and handle which are shown fragmentarily; Fig. 2 is a side elevational view thereof from 40 2-2 of Fig. 1 with the mop strands removed and the handle shown fragmentarily; Fig. 3 is a bottom view of the mop head from 3-3 of Fig. 1 with the handle and mop strands removed, and Fig. 4 is a side elevational view of my mop head in connection with the mop strands without the handle, showing the strands supported for shipment without the handle, the strands being shown fragmentarily.

50 Similar characters of reference refer to similar parts and portions throughout the several views of the drawings.

The mop handle 1, mop head 2, mop strands 3, bolt 4, constitute the principal 55 parts and portions of my mop.

The handle 1 is similar to the conventional

handle, and is provided near its one end with a transversely extending hole 1^a therethrough. The mop head 2 is positioned over the end of the handle 1 and consists of two 60 extended, semi-cylindrical portions 2^a and 2^b which extend part way around and tend to clamp the mop handle. The extended portions 2^a and 2^b are connected by means of an integral band portion 2^c which widens out 65 as it joins the extended portions 2^a and 2^b and which with extended portions forms a substantially oval opening. The mop strands 4 are positioned within the oval opening formed by the band 2^c and the lower side 70 edges of the extended portions 2^a and 2^b. When the extended portions 2^a and 2^b are brought together, the mop strands are held 75 tightly and rigidly within the opening. The semi-cylindrical portions 2^a and 2^b of the 75 mop head are provided with oppositely opposed holes 2^d and 2^e respectively therein which align with the before-mentioned transversely extending hole 1^a in the mop handle 1. Extending through the aligned holes 2^d, 1^a 80 and 2^e in the semi-cylindrical portion 2^a, the handle 1 and the portion 2^b respectively is a bolt 4 which secures the portions 2^a and 2^b to the handle 1. The bolt 4 is provided with a wing nut 4^a so that the mop head may 85 be readily removed or placed on the mop handle. The bolt 4 also holds the mop head in clamped position around the mop strands for shipping.

The mop is made up as follows: The 90 strands used to make up the mop are positioned over the band portion 2^c so that the opposite ends are of equal length on the opposite sides.

The opening formed of the band 2^c and 95 the lower sides of the portions 2^a and 2^b is filled with strands of mop head. When the opening is filled the members 2^a and 2^b are pressed together until the strands of the mop are held in position. Then the bolt 4 is 100 thrust through the holes 2^d and 2^e in the portions 2^a and 2^b and is secured there by means of the wing nut 4^a. The mop head and mop are then ready for shipment, transportation or sale as desired and the handle may 105 be inserted after shipment or the handle may be positioned in the mop head before shipment which is done as follows:

The one end of the handle member is placed in one of the semi-cylindrical portions 2^a so that the hole 1^a therein alines with the hole 2^d in the semi-cylindrical portion.

The bolt 4 is thrust through, the other semi-cylindrical portion 2^b is placed over the end of the bolt and the wing nut 4^a is screwed on, securing the mop head to the mop handle.

Though I have shown a particular construction, combination and arrangement of parts and portions, I do not wish to be limited to this particular construction, combination and arrangement, but desire to include in the scope of my invention the construction, combination and arrangement substantially as set forth in the appended claims.

It is obvious that with this construction there is provided a mop head in the form of two semi-cylindrical portions which, when the two portions 2^a and 2^b are held together by the bolt 4, a cylindrical member is formed for receiving the handle 1; that when they are held together, they grip the strands of the mop and securely hold them from moving or becoming loose between the band and the semicylindrical portions 2^a and 2^b; that the head is secured to the handle by means of a bolt 4 and the curvature of the semi-cylindrical portions; that the head with the mop may be with or without the handle; and if shipped without the handle, the bolt between the two semicylindrical portions will hold the mop strands securely in proper position ready to receive the handle; that the handle is secured rigidly and quickly removable in the cylindrical member formed by the two semicylindrical portions 2^a and 2^b and will not loosen or get out of order.

Having thus described my invention, what I claim as new and desire to secure by Letters Patent is:

1. In a mop head of the class described, 40 a pair of plain, smooth, semi-cylindrical,

non-overlapping clamp portions adapted to fit on a handle and be spaced at their edges, a band connecting the lower ends thereof forming a loop for clamping the mop strands, a bolt extending through holes in said clamp portions and said handle and adapted to simultaneously clamp said band on said mop strands and said clamp portions in rigid spaced relation on said handle.

2. In a mop head of the class described, a pair of plain, smooth, semi-cylindrical, 55 non-overlapping clamp portions adapted to fit on the end of a handle, a band connecting the lower ends thereof forming a clamp for clamping the mop strands, and a bolt extending through holes in said clamp portions for 60 clamping said mop strands between the ends of said clamp portions and said band whereby said mop head may be shipped with the strands clamped in position without the handle.

3. In a mop head of the class described, a pair of semi-cylindrical, non-overlapping clamp portions adapted to fit on the end of a handle and be separated at their edges, each portion provided with a bolt hole therein at its middle portion, an integral mop strand clamping band joining the lower ends thereof provided with widened ends co-extensive with the width of said clamp portions and a bolt extending through said holes in said clamp portions adapted to clamp said band and said widened ends on the mop strands and hold said strands in rigid relation to said mop head, either with or without the handle.

In testimony whereof, I have hereunto set my hand at San Diego, California, this 9th day of August, 1927.

CARL M. HUGULEY
